UNITED STATES PATENT OFFICE.

WALTER LUTTRINGHAUS, OF CHICAGO, ILLINOIS.

DESIGN FOR A COFFEE OR TEA POT.

44,210.

Specification for Design.

Patented June 17, 1913.

Application filed April 5, 1913. Serial No. 759,222. Term of patent 3½ years.

To all whom it may concern:

Be it known that I, WALTER LUTTRINGHAUS, a citizen of the United States, residing at Chicago, in the county of Cook and State of Illinois, have invented a new, original, and ornamental Design for Coffee or Tea Pots, of which the following is a specification, reference being had to the accompanying drawing, forming part thereof.

In the drawing the figure is a view in side elevation of a pot illustrating my new design and embodying the configuration of the body and top of the pot together with the spout with which the body is provided at or near its top.

I claim:

The ornamental design for a coffee or tea pot as shown and described.

WALTER LUTTRINGHAUS.
